to The Art Metal Company, Cleveland Ohio, a
corporation of Ohio

Application March 23, 1944, Serial No. 113,015

Term of patent 14 years

(Cl. D83—1)

To all whom it may concern:

Be it known that we, George E. Glatthar and Joseph Terr, citizens of the United States and residents of University Heights and Cleveland Heights, respectively, in the county of Cuyahoga and State of Ohio, have invented a new, original, and ornamental Design for an Ultraviolet Sterilizer, of which the following is a specification, reference being had to the accompanying drawing, forming a part thereof.

In said drawing, Fig. 1 is an enlarged perspective view of an ultraviolet sterilizer showing our new design; Fig. 2 is a bottom plan view; Fig. 3 is a top plan view; and Fig. 4 is an end elevational view thereof.

We claim:

The ornamental design for an ultraviolet sterilizer, substantially as shown.
